[57] CLAIM

The ornamental design for a bottle, as shown and described.

DESCRIPTION

FIG. 1 is a front elevational view of a bottle embodying my new design;

FIG. 2 is a right side elevational view thereof;

FIG. 3 is a top plan view thereof; and

FIG. 4 is a bottom plan view thereof.

The rear elevational and left-side elevational views are not shown and are essentially mirror images of the front elevational and right-side elevational views shown in FIGS. 1 and 2, respectively.
